(57) **CLAIM**

The ornamental design for an ultrapure water quality point of delivery dispenser, as shown.

DESCRIPTION

The dispenser, which can attach to a support, is a remote, stand-alone dispenser for use with a water purification system.

FIG. 1 is a first perspective view of the ultrapure water quality point of delivery dispenser;

FIG. 2 is a second perspective view of the ultrapure water quality point of delivery dispenser;

FIG. 3 is a front view of the ultrapure water quality point of delivery dispenser;

FIG. 4 is a rear view of the ultrapure water quality point of delivery dispenser;

FIG. 5 is a first side view of the ultrapure water quality point of delivery dispenser;

FIG. 6 is a second side view of the ultrapure water quality point of delivery dispenser;

FIG. 7 is a top view of the ultrapure water quality point of delivery dispenser; and,

FIG. 8 is a bottom view of the ultrapure water quality point of delivery dispenser.

The broken line showing is included for the purpose of illustrating and forms no part of the claimed design.
